US00D745905S

(12) **United States Design Patent**
Jin

(10) **Patent No.:** **US D745,905 S**
(45) **Date of Patent:** **** Dec. 22, 2015**

(54) **FIBER THERMAL STRIPPING DEVICE**

(71) Applicant: **DH INFOTECH (WEIHAI) INC.**,
WeiHai, Shandong Province (CN)

(72) Inventor: **Xun Jin**, WeiHai (CN)

(73) Assignee: **DH INFOTECH (WEIHAI) INC.**,
WeiHai, Shandong Province (TW)

(**) Term: **14 Years**

(21) Appl. No.: **29/476,690**

(22) Filed: **Dec. 16, 2013**

(30) **Foreign Application Priority Data**

Oct. 11, 2013 (CN) 2013 3 0479407

(51) **LOC (10) Cl.** **15-09**

(52) **U.S. Cl.**
USPC **D15/144**

(58) **Field of Classification Search**

USPC D15/144, 144.1, 144.2

(57) **CLAIM**

The ornamental design for a fiber thermal stripping device, as shown and described.

DESCRIPTION

FIG. 1 is a front, bottom perspective view of a fiber thermal stripping device showing my new design;
FIG. 2 is a front, top perspective view thereof;
FIG. 3 is a rear, bottom perspective view thereof;
FIG. 4 is a rear, top perspective view thereof;
FIG. 5 is a front elevational view thereof;
FIG. 6 is a rear elevational thereof;
FIG. 7 is a top plan view thereof;
FIG. 8 is a bottom plan view thereof;
FIG. 9 is a right side view thereof; and,
FIG. 10 is a left side view thereof.

The broken lines in the drawings depict unclaimed environmental subject matter.
